UNITED STATES PATENT OFFICE.

EDWARD E. BURR, OF CHICAGO, ILLINOIS.

DESIGN FOR AN AUTOMOBILE RADIATOR-CAP ORNAMENT.

Application filed July 29, 1927. Serial No. 22,950. Term of patent 3½ years.

To all whom it may concern:

Be it known that I, EDWARD E. BURR, a citizen of the United States, residing at Chicago, in the county of Cook and State of Illinois, have invented a new, original, and ornamental Design for an Automobile Radiator-Cap Ornament, of which the following is a specification, reference being had to the accompanying drawing, forming part thereof.

Fig. 1 is a front elevational view of the ornament embodying the invention, and Fig. 2 is a side elevational view of the same.

I claim:

The ornamental design for an automobile radiator cap ornament as shown.

EDWARD E. BURR.
